UNITED STATES PATENT OFFICE.

EDWARD D. LEVY, OF SPRINGFIELD, MISSOURI, AND HENRY W. JACOBS, OF TOPEKA,
KANSAS.

TANK-CAR.

1,173,443.

Specification of Letters Patent. Patented Feb. 29, 1916.

Application filed July 12, 1915. Serial No. 39,311.

To all whom it may concern:

Be it known that we, EDWARD D. LEVY and HENRY W. JACOBS, citizens of the United States, residing at Springfield, in 5 the county of Greene and State of Missouri, and Topeka, in the county of Shawnee and State of Kansas, respectively, have invented certain new and useful Improvements in Tank-Cars, of which the following is a description, reference being had to the accompanying drawings, which form a part of our specification.

Our invention relates to tank cars made of steel sections having their sides flanged 15 so as to extend substantially at right angles thereto, with the abutting-flanged sides of the various sections arranged to extend outwardly; the sections being preferably arranged to extend circumferentially, so that 20 the adjacent flanges will provide circumferential ribs adapted to be secured together on the outside of the car.

The object of our invention is to provide a tank car possessing the element of safety, 25 of a degree greater than that obtainable with the constructions at present in use; and, at the same time, a construction which will be inexpensive to manufacture.

Our invention contemplates a construction 30 wherein all the seams between the various sections or portions of which the car is constructed, and which are subjected to strains, will be located on the outside of the car where they may be readily accessible for 35 the purposes of repair and the like, thereby eliminating the difficulties and dangers at present encountered in making repairs to tank cars as heretofore constructed.

Another object of our invention is to provide 40 a tank car construction provided with means for preventing rolling or sidewise movement of the tank on its underframe; and, at the same time, provide means which will effectually prevent the tank from surging 45 longitudinally on its underframe.

A further object of our invention is to provide 50 a tank car having means for supporting the running-boards and the various heater-pipes; said means being so arranged that these elements will be entirely supported 55 by the external rivet-seams of the shells or sections constituting the tank car.

Another object of our invention is to provide 55 an outlet or drain for the tank car of such construction that sealing of the valve-drain at the bottom of the tank car will be

unnecessary, while, at the same time, the drain or outlet will be of such construction that in case of its becoming broken in a wreck or derailment, the outlet-valve will 60 not be opened thereby to allow the contents of the tank car to drain and become lost.

The invention possesses other advantages inherent in the construction, which will be apparent from the following detailed description.

In the drawings: Figure 1 is a side elevation and partial longitudinal sectional view, illustrating the general outside construction as well as the arrangement of the 70 heater-pipes and longitudinal underframe anchor of the tank car. Fig. 2 is a partial end elevation and partial sectional view, the sectional view being taken on the line A—A of Fig. 1 to more clearly show the method 75 of supporting the heater-pipes or coils, and also the manner for securing the running-board bracket or support. Fig. 3 is an enlarged longitudinal sectional view, taken through the central bottom portion of the 80 tank intermediate of its ends to more clearly illustrate the application and construction of the longitudinal frame-anchor, as well as the location and manner of application of the heater-pipes or coils and the tank-valve 85 and drain. Fig. 4 is a partial transverse sectional view, taken on the line B—B of Fig. 1, to-wit through the longitudinal frame-anchor also shown in Fig. 3. Fig. 5 is a detail view, partially in section and 90 partially in elevation, illustrating one form of longitudinal joint and arrangement of a filling-strip between the transversely flanged ends of the shells or sections for the purpose 95 of providing a metallic running-board. Fig. 6 is an enlarged detail illustrating the method of providing transverse anchors for connecting the tank to the underframe of the car, so as to prevent sidewise rolling of the tank on the underframe; the anchor attaching member is shown in place between the 100 ends of the stay-sheet member; a portion only of the stay-sheet member being shown, with the adjacent section of the tank removed. Fig. 7 is a side elevation and partial longitudinal sectional view illustrating a modified form of our improved tank car; showing, like in Fig. 1, the general outside construction as well as the arrangement of 105 the heater pipes and the longitudinal underframe of the car. Fig. 8 is an enlarged partial side and partial sectional view of

several sections, illustrating another modified form of our invention; the figure showing one end and adjacent section, with the tank-head or end member secured in place. Fig. 9 is a vertical sectional view, taken on the line 9—9 of Fig. 8, looking in the direction of the arrows.

In the particular exemplification of our invention, as illustrated in the drawings, the tank car is composed of a series of metallic sections 10, the sides whereof are flanged and presented outwardly, as can more clearly be seen at 10^a in Figs. 3 and 4. The sections are preferably formed of continuous sheets arranged transversely of the tank car and bent into the cylindrical form or ring as shown, with the ends of the sheets or sections preferably secured together by welding; the welded joint in such construction being preferably arranged at the top of the tank car so as to extend parallel with the longitudinal axis thereof, as shown at 10^c in Fig. 2.

Instead of uniting the ends of the various sections as just described, the ends may be flanged or bent outwardly, as shown at 10^b in Fig. 5, so as to permit being riveted together, as shown at 11 in said figure. It is preferable to have the ends bent to such an extent as to permit at least a double row of rivets as shown, which will provide a seam extending transversely of each section 10 adjacent the top of the tank as shown in Fig. 5.

We prefer to provide the seams just referred to with a filling-strip 12, see Fig. 5, the filling-strip 12 being made of a length greater than the bent-up ends of the sections so as to provide an extended portion, which is bent at an angle to the seam-forming portion so as to extend horizontally and thereby provide a metal running-board extending lengthwise of each section and therefore lengthwise of the tank car, as more clearly shown to the right in Fig. 1. The outwardly extending portion of this filling strip 12 is supported by means of brackets 13, each of which comprises a plate or member arranged intermediate of the adjoining sides of the different sections 10; the plates or brackets 13 are arranged to act as a portion of the filling strips between the transversely extending seams of the tank car. The remainder or main portion of the transverse seams are provided with a filling strip 14 intermediate of the adjacent flanged sides of the respective sections, thereby materially strengthening the construction in a radial manner, and, at the same time, providing a good calking strip for producing a fluid-tight joint. As very clearly shown in Fig. 2, the filling-strip 14 is cut away to receive the bracket-member 13, which, of course, is made of a thickness equal to that of the filling strip 14. After the filling-strip 14 has been

inserted between the flanged sides of the respective sections, the flange-portions are secured together in any suitable manner, as, for example, by means of rivets indicated at 15, which pass entirely through the adjacent flanged portions and the filling-strip and provide fluid-tight connections.

The filling-strips 14, where they extend about the lower part of the tank car, are preferably provided with inward extensions 75 or portions 14^a, as shown in Figs. 2 and 4, in order to provide a suitable bracket or support for the heater-coils 16 arranged within the tank car along the bottom-portion thereof. The extended or bracket-portions 14^a 80 are preferably provided with suitable holes or sockets 17, see Fig. 4, arranged to receive the various portions or lines of the heater-coil 16. The inwardly extended portions or brackets 14^a are also provided with the enlarged openings 18, see Figs. 2 and 4, arranged at points adjacent the walls of the tank car so as to afford proper circulation for the fluid contained in the tank, and thus also permit the tank to be completely 90 drained.

In order to prevent longitudinal movement or slipping of the tank on the under-frame, we provide a longitudinally disposed frame-anchor casting 19, see Figs. 3 and 4, 95 which is arranged to form a lower portion of the tank shell; the length of the anchor-casting 19 being preferably commensurate with the width of one of the intermediate metallic sections 10 of the tank car, so that 100 the ends of the longitudinal anchor-casting 19 may be secured to the flanged sides 10^a of the adjacent sections 10, as shown in Fig. 3. The connection between the anchor-casting 19 and the sections are preferably made 105 by riveting the respective parts together with an intermediate filling or calking strip 14, as shown in Fig. 3.

The anchor-casting 19 also has the ends of the shortened or middle section 10 secured 110 to it, see Fig. 4; the anchor-casting 19 being provided with the flanged sides 19^a to which the flanged or bent ends 10^a of the section 10 are secured by means of suitable rivets, as shown in Fig. 4. In order to provide a 115 fluid-tight connection, we prefer to weld the entire joint between the anchor-casting 19 and the sectional wall of the tank car, preferably employing the autogenous method so as to produce the joint, as indicated at 20 in 120 Fig. 4.

Aside from acting as a frame-anchor, the casting 19 is also intended to provide a suitable valve-seat 21 for the valve 22. Valve 22 is preferably provided with valve stem 125 22^a which extends to the top of the tank-car, so that it may be operated through the man-hole 23 shown in Fig. 1. The man-hole is provided with a suitable cover-plate 25 which may be sealed to the cover or top 130

of the tank-dome 26 after the car has been filled.

Anchor-casting 19 is provided with the downwardly presented walls 19^b extending lengthwise thereof, which are adapted to come intermediate of the center-sills 27, 27, see Fig. 4. The casting 19 is also provided with a discharge spout or port 19^c, arranged between the walls 19^b; the lower end of the port 19^c being reinforced by the web-portion 19^d, formed integral with walls 19^b, thereby also reinforcing the side walls 19^b. The web-portion 19^d provides a securing point for the spout or extension 28 connected with the drain-port 19^c; the spout or extension 28 being secured to the web 19^d by means of the bolts 28^a. The downwardly presented walls or flanges 19^b of the anchor-casting are also provided at their bottoms with the inwardly presented flanges 19^e, to which cover-plate 29 may be secured, by means of suitable bolts, as shown in Fig. 4. As is evident from the construction, the inwardly presented webs or flanges, and the cover-plate, together with the webs 19^d, will reinforce the side walls 19^b, and therefore also the center-sills 27, 27. The lower end of spout or extension 28 is preferably shown threaded to receive a cap 30.

We prefer to provide the anchor-casting 19 with the horizontally disposed flanges 19^e, adapted to rest on top of the center sills 27, see Fig. 4, while the downwardly presented walls 19^b abut against the inner sides of the center-sills 27, 27. The construction of an anchor-casting shown and described will prevent the center-sills buckling either upwardly or downwardly by reason of the flange-portions 19^e and the cover-plate 29. The anchor-casting 19 is also provided at its ends with the vertically disposed flange-portions 19^e, which are adapted to abut against filler-blocks 31, 31, which are secured between the center-sills 27, 27 and securely riveted thereto, as shown in Fig. 3. This construction and arrangement will prevent longitudinal movement of the anchor-casting between the center-sills and therefore also of the tank.

The spout or extension 28 is preferably made lighter in construction than the outlet port 19^c formed in the anchor-casting, so that, in case of wreck or derailment, should the spout or extension 28 become broken, it will not necessarily break the port-portion 19^c provided with the valve-seat and therefore may prevent the valve becoming unseated; the construction being intended to avoid the possibility in case of accidents, of allowing the contents to drain off. The anchor-casting 19 is also shown provided with suitable flanged openings 19^h, 19^h, see Fig. 3, adapted to receive the ends of the heater-coils 16; the flanged openings 19^h being also intended to receive the inlet and

outlet pipes 32 and 33, respectively. Pipe 32 is intended to be connected with a suitable source of heat-supplying medium, while the pipe 33 will, in this instance, constitute the discharge or return pipe. As previously described, the heater-pipes are arranged along the bottom of the tank-car, being seated in the slots 17 arranged in the extension 14^a of the filler-strip arranged at points intermediate of the ends of the tank-car; the extensions 14^a of the filler-strip, near the ends of the tank car, being preferably provided with holes, instead of slots, as shown in Fig. 2, for the passage of the heater-coils or pipes 16, so as to firmly hold the heater-coils against displacement, and yet, at the same time, permit the heater-coils to be easily assembled.

As more clearly shown in Fig. 2, the cylindrical tank is supported by means of the body-bolster 34, which is preferably provided with the upwardly extending block or metallic lug 35 provided with a curved surface conforming to the curvature of the tank; the wall of the tank, at this point, being preferably provided with filling blocks 36 of suitable thickness and arranged as shown in Fig. 2.

In order to prevent sidewise movement or rolling of the tank, we provide anchors 37, 95 see Fig. 6, which are preferably in the nature of eye-bolts having their lower ends threaded and extending through the tie-rod 38 which is riveted or otherwise secured to the center-sills 27 and extends transversely 100 of the underframe; the outer ends of the tie-rod 38 being preferably bent at a suitable angle to permit of the passage therethrough of the anchor 37; the latter being firmly maintained in position by means of the nut 39. The anchor 37 is pivotally secured to the clamp-member 40, which latter is shown riveted to the extended plate or member 41, which may either be made integral with the filling or calking strip 14, 110 or be made separate therefrom, as shown in Fig. 6. In order to permit of this construction and arrangement, the filling-strip 14 is shortened or cut away sufficiently to permit the insertion of the plate or member 41, in a manner similar to the method employed where the brackets 13 are inserted as previously described. It will be understood, of course, that similar anchors are provided on both sides of the tank, as shown in dotted 120 lines in Fig. 2, and any desired number being employed; the anchors being arranged in alinement with the circumferential seams or ribs of the tank.

The juncture between the filling strip 14 and the plate or member 41, as well as the juncture between the filling strip 14 and the brackets 13, may either be calked tight or welded in any suitable manner, preferably by the autogenous method.

- The method of providing the side anchors, as described, provides a surface adapted to receive quite a number of rivets, and, at the same time, permits sufficient flexing to accommodate any longitudinal expansion or contraction of the tank, due to the uneven temperatures to which the tank may be subjected, without causing the circumferential seams to spring or become affected.
- 10 The ends of the tank car are provided with ladders 42, leading upward to the running-boards 12 arranged along the upper sides of the tank, and the running-boards are also preferably provided with the hand-rails 43 which extend lengthwise of the car and may also be continued across the ends of the tank car, as shown in Fig. 2, so as to permit the brakeman or operator to cross from one running-board to the other with safety.
- 15 The dome 26 is provided with a suitable safety valve 44, which may be set to the desired pressure for testing, in accordance with the government regulations or rules. The concavo-convex or dished ends 45, 45, are also provided with outwardly presented flanges, as shown at 46, in Fig. 1, so as to permit the heads or ends 45 to be riveted or secured to the flanged sides of the adjacent shell-sections 10.
- 20 With our improved construction, all seams will be arranged on the outside of the tank, where they are accessible for immediate inspection and repair without the necessity of first having to empty the tank.
- 25 The importance of this construction is greater than may seem apparent, as many serious accidents and situations have been encountered with tank cars as heretofore constructed, while passing over a bed of hot cinders, due to leaky joints.
- 30 With our improved construction, should a seam or joint become leaky while the car is in transit or filled, it is evident that the joint may be immediately repaired on the exterior of the tank without first being emptied, thereby obviating the dangers heretofore encountered.
- 35 As is apparent from the construction shown and described, the tank may be constructed independent of the car-frame and subsequently placed thereon and secured thereto by the longitudinal anchor-casting 19 and the tie-anchors 37; the longitudinal anchor 19 fitting between the center-sills intermediate of the filling-blocks 31. The cover-plate 29 is then secured in place by means of bolts, as shown in Figs. 3 and 4, so that the tank will be securely fastened to the frame of the car. It is also evident therefore that the tank may be readily removed by simply releasing the tie-anchors 37 and removing cover-plate 29.
- 40 In the modified form of our invention, as illustrated in Fig. 7, the tank car is composed of a series of metallic sections 10^a, the

sides whereof are flanged and presented outwardly in the same manner as the sections of the tank car illustrated in the first six figures of the drawings. In the modified form, as illustrated in Fig. 7, however, the sections, which constitute the tank-portion of the car, are each provided with circumferentially extending ribs or corrugations 47 whereby the respective sections 10^a will not only be strengthened in a transverse 75 or radial manner, but the sections are adapted to permit of longitudinal expansion of the tank car. The sections, like the sections in the construction illustrated in the first six figures of the drawings, are preferably formed of continuous sheets arranged transversely of the tank-car and bent into the cylindrical form or ring as shown; the end of the sheet or section being preferably secured together by welding. If desired, 80 the ends of the sheets, constituting the sections, may be flanged or bent outwardly as shown at 10^b in Fig. 5, so as to permit the ends being riveted together in the same manner as in the previously described construction.

The circumferentially disposed seams between adjacent sections are preferably provided with sealing strips as in the previously described construction; and the running-board, which extends lengthwise of the tank-car, may be formed in the same manner as that previously described; or, if desired, the running board may be otherwise formed and secured in place.

As the general arrangement and manner of securing the heater coils or pipes is similar to that shown in the first figures of the drawings, a detailed description thereof will be unnecessary. The tank car shown in Fig. 7, like the one shown in Fig. 1, is provided with a similar longitudinally disposed frame-member casting or anchor 19 secured in place in a similar manner and also providing a suitable valve-seat and downwardly presented extension or spout for the discharge adapted to receive the extension or nozzle 28, shown in Figs. 3 and 4, all of which is to be intended to be arranged between the longitudinal center sills of the 115 car. The anchor-casting, illustrated in Fig. 7, is intended to be identical with that shown in Figs. 1, 3 and 4.

In Figs. 8 and 9, we show a third modified form of the invention in so far as the 120 construction of the respective sections of the tank car are concerned. In this modification, the sections 10^a are formed of sheet metal provided with the ribs or corrugations 48 extending transversely of the sheet so as 125 to extend longitudinally of the tank car when the sheets have been bent into the cylindrical form or ring, as shown in Fig. 8. The corrugations extend substantially throughout the width of the sheet, with the 130

ends of the corrugations tapering or diminishing in depth, as can more clearly be seen to the left of Fig. 8, in order to permit the sides of the sheet or sections to be flanged, as shown at 49, formed so as to be presented outwardly in order that the connections between the various sections may be made on the outside of the tank car. The seam or joint between the respective sections 10 is preferably provided with an intermediate sealing-strip 14^a riveted between the abutting flanged ends of adjacent sections. The ends of the tank car, as illustrated in Figs. 7 and 8, are closed by the end-members or heads 45, made concavo-convex similar to the ends of the tank car shown in Fig. 1; the heads or ends having their peripheries flanged so as to extend outwardly in a similar manner to the flanged sides of the various sections. The longitudinally disposed 20 ribs or corrugations 48 will naturally strengthen the respective sections both longitudinally and radially, at the same time permit the necessary expansion and contraction of the tank resulting from variations in temperature.

The tank car in other respects may be similar to that previously described, with a portion of the calking or sealing strip 14^a cut away at the proper point to receive the bracket-members 13^c, see Fig. 9, to act as a support for the running boards arranged longitudinally of the tank car.

With our improved constructions, repairs 35 on the tank-proper may be easily made because of the fact that the various seams, formed by the above sections from which the tank is constructed, are located on the outside of the tank, and therefore accessible, 40 thus obviating the necessity of first scalding out the tank, as is the case with constructions as at present in use, with the result that the expense of maintenance is materially lessened. At the same time, constructions are provided possessing greater 45 radial strength by reason of the circumferential ribs resulting from the employment of the flanged sections and the reinforcing filling or calking strips. The 50 strength of the tank car may be increased if desired by the employment of sections of less width, thereby providing a greater number of cylindrical seams due to the employment of a greater number of cylindrical sections 55 necessary to provide a tank car of the desired size; or by providing the corrugations or ribs shown and described.

It is evident from the constructions shown and described that if any of the joints of 60 the tank car should become leaky, the seams or joints may be quickly repaired on the car exterior regardless of whether or not the tank is filled or emptied, as all of the seams or joints are located on the tank car exterior. The importance of such a construc-

tion will be readily apparent. Serious conditions have resulted in the use of the ordinary type of tank car where leaks have been sprung while the car is in transit or on a siding due to the fact that such leaks could 70 not be repaired until after the tank car had been emptied; and, in addition to the serious accidents, such constructions have also resulted in a considerable loss of the oil because of the inability to make repairs while 75 the car is filled with oil.

We have shown and described what we believe to be the best forms of our invention; certain details of construction, however, may be modified without departing from the 80 spirit of the invention, and we do not wish to be understood, therefore, as limiting ourselves to the exact construction shown and described.

What we claim is:

1. A tank car composed of a series of cylindrical sections, the sides whereof are flanged outwardly, sealing or calking means arranged between the flanged sides of adjacent sections, a portion of said sealing or 90 calking means being extended outwardly beyond the outer periphery of said flanged sides, and means secured to said extended portion whereby the tank car is anchored to the car underframe against sidewise movement. 95

2. In combination with the center sills of the underframe of a car, a tank car composed of a series of cylindrical sections composed of sheet metal, the sides whereof are 100 flanged outwardly so as to provide circumferentially extending ribs, sealing or calking means intermediate of the flanged portions of adjacent sections, a portion of said calking or sealing means being extended 105 outwardly beyond the periphery of the flanged sides of the sections, and anchoring means secured to said extended portions of the sealing or calking means and to the center sills of the car underframe. 110

3. In combination with the center sills of the underframe of a car, a tank car composed of a series of cylindrical sections formed of sheet metal, the sides whereof are flanged so as to present outwardly extending 115 circumferential ribs, a segment of one of said sections being formed by an anchor casting and secured thereto, said casting being adapted to extend intermediate of the longitudinal center sills of the car underframe and prevent movement of the tank lengthwise of the car underframe. 120

4. In combination with the center sills of a car underframe, a tank composed of a series of cylindrical sheet metal sections, the 125 adjacent sides whereof are flanged outwardly so as to present circumferential ribs externally of the tank whereby the respective sections are secured together, one of said sections being provided with an an- 130

chor-casting forming a segment of the cylindrical drum or section and provided with outwardly presented flanged portions adapted to be secured to the outwardly presented 5 bent ends of said section, said anchor casting being arranged to extend between the longitudinal center sills of the car, and means arranged intermediate of the ends of said casting and the center sills whereby longitudinal 10 movement of the tank will be prevented.

5. In combination with the longitudinal center sills of a car underframe, a tank composed of a series of cylindrical sections, the sides whereof are flanged outwardly, means 15 whereby the adjacent flanged sides of the respective sections are secured together externally of the tank, an anchor casting adapted to constitute a portion of the bottom of one of said sections, the sides and ends of said 20 casting being flanged outwardly and adapted to be secured to the outwardly presented ends and sides of the sections, said casting being adapted to extend intermediate of the longitudinal center sills of the underframe 25 so as to prevent movement of the tank lengthwise of the underframe, said anchor casting being provided with a valve-seat terminating in a discharge port, and a discharge spout removably secured to said discharge 30 port.

6. A tank car consisting of a series of flanged sections, the flanges whereof are presented outwardly, means whereby the flanged portions of adjacent sections are 35 secured together, and an anchor casting constituting a portion of one of said sections, said anchor casting and the registering section being provided with flanges presented outwardly whereby the casting and said section 40 may be secured together externally of the tank, the casting comprising a pair of downwardly presented parallel walls arranged to extend intermediate of the center sills of the car underframe, said casting being 45 provided with a discharge port intermediate of the downwardly presented parallel walls.

7. A tank car composed of a series of cylindrical sections, the sides whereof are 50 flanged outwardly so as to provide external circumferential ribs whereby the respective sections are secured together, and an anchor or casting constituting a portion of one of said sections, said anchor casting being provided with laterally disposed flanges 55 adapted to extend across the top of the center sills of the car underframe and with downwardly presented parallel portions arranged to extend intermediate of the center 60 sills of the car underframe, said anchor casting being provided with a valved discharge port arranged intermediate of said downwardly presented portions, and means re-

movably secured to said valved discharge port.

8. A tank car provided with heater coils and composed of a series of cylindrical sections, the sides whereof are flanged outwardly so as to provide circumferentially disposed ribs whereby the respective sections 70 are secured together on the tank car exterior, dished ends or heads having outwardly presented peripheral flanges adapted to be secured to the flanged sides of the adjacent sections, an anchor casting constituting a portion of the tank, having outwardly presented flanges whereby the casting is secured to the sections of the tank, said casting being provided with a discharge opening and with openings adapted to receive 80 the inlet and outlet ends of the heater coils and with portions arranged parallel and intermediate of the longitudinal center sills of the car underframe, and a discharge spout removably secured to the discharge opening 85 of the anchor casting.

9. In combination with the center sills of the car-underframe provided with stops or abutting means, a tank car composed of cylindrical sections having their ends flanged 90 outwardly to provide seams externally of the tank, and an anchor casting constituting a portion of the tank having outwardly extended flanged sides adapted to be secured to the adjacent portions of the sections, 95 said anchor-casting being provided with portions adapted to engage the longitudinal center sills of the car underframe to prevent movement of the tank longitudinally of the car underframe.

10. A tank car composed of a series of cylindrical sheet metal sections provided with outwardly presented corrugations, the ends of the sections being flanged outwardly, means whereby the flanged ends of the sections are secured together externally of the tank car, and means adapted to constitute a segmental portion of one of said sections and secured thereto for anchoring the tank, to the car-underframe against longitudinal 110 movement.

11. A tank car composed of a series of flanged sections, the flanges whereof are disposed outwardly, and sealing or filling strips arranged between the flanges of adjacent 115 sections, a portion of said strips being extended beyond the peripheries of adjacent sections so as to provide attaching extensions, the flanges and intervening strips being secured together by external rivets.
